APPARATUS FOR DECORATING ARTICLES

Harold Horine, Hollister, Mo.

Application January 23, 1935, Serial No. 3,167

2 Claims. (Cl. 41—1)

This invention relates to apparatus for decorating articles.

One of the objects of the invention is the provision of a method for applying irregular and grotesque designs to articles of manufacture such as vases and the like, which articles are constructed of relatively porous walls of concrete formation.

Another feature of the present invention is to provide an apparatus in the nature of a bin so constructed as to utilize the bottom of the bin for a common bottom for a plurality of chambers.

Another feature of the present invention is to provide a bin of such a construction that a plurality of valve rods may be operated from the open top of the bin by a single valve operating rod common to all of the valve rods.

Further objects of the invention are to provide a very economical method of decorating articles that eliminates the skill of master craftsman designers, and that is free from a technical laboratory control.

A still further object of the invention is the provision of an apparatus for conducting the method which is strong, compact and durable, thoroughly reliable for its intended purpose, having very few parts that need repair, and that is comparatively inexpensive to manufacture and operate.

With the foregoing and other objects in view the apparatus consists of a novel construction, combination and arrangement of parts as will be hereinafter more specifically described and illustrated in the accompanying drawings, wherein is disclosed an embodiment of the invention, but it is to be understood that changes, variations and modifications may be resorted to without departing from the spirit of the claims hereunto appended.

In the drawings wherein like reference characters denote corresponding parts throughout the several views:

Figure 1 is a side elevation of the bin in accordance with the present invention and showing the position of the operator's hand for controlling the discharge when carrying on the method.

Figure 2 is a section taken substantially on line 2—2 and looking in the direction of the arrows.

Figure 3 is a perspective view illustrating the method by which the multiple streams of colored cementitious fluid material are applied to the article.

Figure 4 is a fragmentary vertical section taken substantially on lines 4—4 of Figure 2 and looking in the direction of the arrows.

The apparatus by which the method is carried out will be described in the first instance. Referring to the drawings in detail, wherein is disclosed the preferred embodiment of the apparatus, A indicates generally the bin of segmental configuration including the vertically arranged arcuate side wall 5 to the ends of which are joined the vertically arranged, straight chordwise wall 6 and the lower ends of these side walls 5, 6 are integral with the horizontal bottom wall 10. The top of the bin is opened so that material may be added. The curved rod 8 forms the handle for the bin and on the opposite ends of the handle are hooks 9 which extend through openings in the upper edge of the arcuate side wall 5. 15

In the center of the straight side wall 6 it is formed with an arcuate portion 10 coextensive with the height of this side wall forming a concavity across which are secured centrally apertured bosses 11 spaced one from the other. Mounted in the apertures for sliding movement in the concavity formed by the arcuate portion 10 is a vertical valve operating rod 12, the upper end of which normally projects above the top of the bin. The coil spring 13 embraces an intermediate portion of the valve operating rod 12 and the upper end of this spring bears against the lower face of the upper boss 11. 20 25

For operating the valve operating rod 12, the inner end of a plate handle 14 is secured to the intermediate portion of the valve operating rod 12 and the lower end of the spring 13 bears on the upper end of the handle. The coil spring 13 maintains the valve operating rod 12 and the valves to be presently described, in a retracted position under the tension of the spring. The plate handle 14 has a portion 15 turned upwardly to provide a straight guide channel 16. The handle 14 radiates from the straight side wall 6 of the bin. A gripping member is indicated 40 generally at 17 and this member is stationary and secured to the outer face of the side wall 6 intermediate the ends thereof. This gripping member has a horizontal portion 18 and a depending portion 19 at right angles thereto. The depending portion 19 is overlapped by the flange 15 of the handle and rides in the guide channel 16. 35

When operating the valve operating rod 12, the fingers rest on the horizontal portion 18 and the thumb grips the handle 14 to urge the valve operating rod upwardly against the tension of coil spring 13 to permit material to flow through the valve ports to be presently described. 45 50

The interior of the bin A is divided into a plurality of chambers 20 by the vertical partition 55

walls 21 the inner ends thereof being secured to the concave or arcuate portion 10 of the straight wall 6. The chambers 20 have the bottom wall 7 of the bin common to all of them. The outer 5 ends of the partition wall 21 are joined to the inner face of the arcuate side wall 5.

There are a series of valve ports 23, one for each chamber 20, in the bottom wall 7 arranged in a semi-circle of a relatively small diameter, 10 preferably on a one inch radius so that discharges from the multiple chambers will form a substantially continuous stream. Disposed vertically in the bin A, one for each chamber 20, are vertical valve rods 24, one for each valve port 23 for each 15 chamber, and the lower ends of the valve rods are pointed as at 25 to extend through the valve ports 23 and close these ports. The upper ends of the valve rods 24 extend above the respective chambers 20 and the open top of the bin and 20 each valve rod is anchored to the segmental plate 26. The upper end of the valve operating rod 12 is likewise secured to the segmental plate 26. It will therefore be seen that when the valve operating rod 12 is moved by the handle 14 all 25 of the valve rods 24 will be raised simultaneously and the points 25 will be free of the valve ports 23 thereby permitting material in the multiple bins 20 to flow through the valve ports.

In the method of decorating the articles with 30 the apparatus of the present invention, the articles such as vases, and the like are formed of concrete which in the dry form is relatively porous and open in texture. It will be understood that all concrete articles to be treated by 35 the present method are first submerged in water. Thereafter the articles are submerged in a ground bath of creamy consistency. This bath is a cementitious composition, made up of a mixture of two parts by weight of fine sand and 40 one part by weight of white Portland cement mixed with water to a creamy consistency and either of natural cement color or tinted with coloring matter. The film resulting from immersion in this bath not only fills the voids in 45 the surface of the concrete articles but applies a ground color for the articles.

After the film is removed from the bath and the excess drained therefrom, the next step in the operation is performed without allowing the 50 ground film to set. The article is then placed on a rod 30 that serves as a spindle and the center of the spindle rests in a yoke 31 on the upper end of a vertical standard 32 carried by the drain pan 33. It is usually the practice to carry 55 the bin A on a hook support 34 whereby the bin A is suspended over the drain pan 33.

The article indicated generally at C which for the purpose of illustration is a vase, is held

under the multiple valve ports 23 of the bin in the manner indicated in Figure 3 of the drawings.

In the multiple chambers 20 of the bin is carried cementitious compositions of different colors, a different color being in each chamber. So far as the cementitious composition used in the chambers is concerned, the ingredients are the same and in the same proportions as described for the ground coating or film, with the exception that different concrete coloring matters are added for the different chambers. With one hand the operator then opens the multiple valve ports and multiple streams of varying colors of cementitious material are deposited on the outside of the article, while the article is revolved and moved in various directions while it is being revolved thereby making the irregular motley colored designs over the ground film prior to the time this film sets. The article may then 20 be removed from the spindle 30 and placed to dry in the air.

Having thus described the invention, what is claimed as new is:

1. A dispensing device comprising a bin of segmental configuration including an open top, a bottom wall, an arcuate side wall and a chord-wise wall; said chord-wise wall formed in the center with a concave portion; apertured guide bosses mounted in the channel of the concave portion; a retractile valve operating rod mounted in the channel and extending through the apertures; plural partition walls in the bin radiating from the concave portion to form multiple chambers; said bottom wall formed with a series of valve ports one for each chamber and arranged in a semi-circle, a plurality of valve rods connected to the valve operating rod, and means on the valve operating rod for projecting the same whereby the valve rods are simultaneously opened.

2. A dispensing device comprising a bin including a bottom and side walls and an open top, vertically arranged partition walls in the bin dividing the latter into multiple chambers 45 having the bottom wall of the bin common to the chambers, said bottom wall formed with multiple valve ports one for each chamber, vertically arranged valve rods in the bin one cooperating with each valve port, a vertical valve 50 operating rod carried on the outside of the bin and connected with the top of the valve rods by a common connection, a gripping member secured to the outside of the bin, and means carried by the valve operating rod and coacting 55 with the gripping member for actuating the valve rods.

HAROLD HORINE.
